HAIR TRIMMER

Leonard A. Gesler, Aurora, Ill.

Application June 14, 1937, Serial No. 148,055

10 Claims.

(Cl. 30—31)

This invention relates to a hair trimmer and more particularly to such device having a pick-up roller that will positively pick up the hairs, preferably on the head of a human being, and present 5 such hairs in an outwardly standing position.

To attempt to trim the hair on the head of a human being with an ordinary razor would be disastrous for the reason that the razor could not be properly guided and the hairs would not 10 be picked up and presented to the blade at right angles thereto; hence such trimming attempt would result in cutting unsightly furrows and other irregularities in the hair, thus destroying its good appearance.

15 In the present invention I have overcome these difficulties by providing an attachment or additional structure that may be readily attached to or built into an ordinary razor holder to provide a pick-up roller rotatable in front of the cutting edge of the razor blade in such direction and so constructed as to pick up the hairs of the head and cause them to stand at substantially right angles to the cutting edge of the blade, so that as the hair trimmer is moved over the hair of the 20 head it will positively and effectively trim the same smoothly to give a very uniform and pleasing appearance to the hair after being trimmed, and free from rough places or other unsightly appearance.

25 In the present invention I have also provided means for positively rotating the pick-up roller at the desired speed, either by means of a power roller receiving its rotation from rolling contact on the hair or by means of a suitable motor, such as a spring motor, electric motor, or the like. When a motor is used the power roller will be omitted, but in the absence of a motor the power roller will be provided to furnish the power for 30 driving the pick-up roller by rolling contact with the hair of the head, as referred to above.

35 Among the objects of my invention is to provide a hair trimmer that will trim the hair evenly and smoothly.

40 A further object is to provide a novel pick-up roller for picking up the hairs of the head and present them at substantially right angles to the cutting edge of the blade.

45 A still further object is to provide novel means for positively rotating said pick-up roller at the desired speed.

50 Another object is to so arrange the parts in advance of the cutting edge of the blade that the cutting edge will be presented to the hair at a convenient and effective angle.

55 A further object is to provide such means that

they may be readily incorporated into a safety razor of any of the well known types in such manner as to sell the completed device at a reasonable price.

A still further object is to provide a convenient 5 and effective device of the class described herein, such that a man may trim his own hair without the assistance of anyone else, and either with or without the use of mirrors as desired.

Other objects, advantages and capabilities will 10 later more fully appear.

My invention further resides in the combination, construction and arrangement of parts illustrated in the accompanying drawing, and while I have shown therein preferred embodiments I 15 wish it understood that the same are susceptible of modification and change without departing from the spirit of my invention.

In the drawing:

Fig. 1 is a top plan view of a safety razor showing my invention applied thereto. 20

Fig. 2 is a side elevation of the device shown in Fig. 1.

Fig. 3 is a vertical transverse section taken on the line 3—3 of Fig. 1. 25

Fig. 4 is a perspective detail view of the attachment prior to securing the same to the razor holder.

Fig. 5 is a vertical transverse sectional view of a modified form of my invention. 30

Referring more in detail to the drawing, my invention is shown as applied to a safety razor of the Gillette type, having the usual holder 1, clamping plate 2 and handle 3, the clamping plate 2 being secured to the holder 1 by the screw stud 35 4 screwing into a correspondingly threaded opening in the upper end of the handle, so that by rotation of the handle the blade 5 will be clamped in the usual manner between the clamping plate and the holder. While I have for illustrative 40 purposes shown this particular type of Gillette razor, I wish it understood that my invention is applicable to other forms of Gillette razors as well as other types of razors, it being obvious that when applied to different types or forms of razors 45 the attaching parts will be varied to suit the particular type of razor to which my invention is applied.

For the purpose of providing a suitable mounting for my hair trimming attachment, I have provided a pair of end plates 6 and 7 each provided with lugs 8 bent at the desirable angle thereto (in the present case this angle being 90°), and each of these lugs being formed with openings 9 to receive the attaching screws 10, which are pref- 50

erably provided with slotted heads to receive a screw driver or the like, and be screwed into correspondingly threaded openings 11 in the holder (see Fig. 3), so that the plates 6 and 7 will 5 occupy a position substantially at right angles to the body of the holder and project downwardly therefrom. In applying my device to a safety razor I permit the rear guard teeth 12 to remain on the razor but remove the guard teeth from the 10 front edge, said front edge being preferably shaped as shown at 13 in Fig. 3, this being so that there will be no guard teeth on the front edge of the razor to interfere with my pick-up roller.

Plate 6 is formed adjacent its forward edge with 15 suitably spaced round openings or apertures 14 and 15, while plate 7 is likewise formed with spaced similar apertures 16 and 17, these apertures receiving the shaft or reduced cylindrical ends of the pick-up roller 18 and the power roller 20 19, the former being rotatably mounted in the apertures 14 and 16 and the latter being rotatably mounted in apertures 15 and 17. Fixed upon one end of the shaft or reduced cylindrical end 20 of power roller 19 is a gear 21, and likewise fixed 25 upon the shaft or reduced cylindrical end 22 of the pick-up roller 18 is a small gear 23. Plate 6 is also provided with a cylindrical aperture 24 properly spaced to receive a stub shaft 25, upon which is mounted a gear wheel 26 properly meshing 30 with gears 21 and 23, so as to transmit rotation from power gear 21 to gear 23 for driving the pick-up roller 18. Gear 26 may be either fixed to stub shaft 25 and the latter rotatable in aperture 24, or stub shaft 25 may be fixed in aperture 24 and gear 26 rotatable on the stub shaft, as 35 desired.

Referring to Fig. 3, the line 27 represents the general line of travel of the device over the hair, it being understood that when both the power roller 19 and the adjacent bearing portion of the clamping plate 2 touch the head they are in position 40 for a close trim or fine cut, and when a coarser cut or trim is desired the device will rock about the power roller 19 as a fulcrum, with the 45 adjacent portion of the clamping plate 2 a greater or less distance away from the head, thus giving a wide range of adjustability to the close or coarse cut.

It will be noted that the power roller 19 is provided 50 with a suitable number of spaced discs 28, each being formed around its circumference with a sufficient number of notches or indentations to provide projecting blunt-ended teeth 29, which will sink in between the hairs of the head and in 55 general follow the scalp, the teeth 29 giving added traction because of their more readily taking hold of the scalp. It is also to be noted that the pick-up roller 18 is provided throughout its length with teeth 30 so arranged as to pick up 60 the individual hairs of the head as the device is moved over the head, due to the rotation of the pick-up roller such that the individual hairs will be picked up and presented at approximately right angles to the cutting edge 31 of the blade 5.

I have shown an effective arrangement of 65 teeth 30 on pick-up roller 18 in the drawing, which consists in effect of providing the pick-up roller with a circumferential helical groove 32, which may be single, double, triple, or other pitch, 70 as desired, which grooves result in the formation of correspondingly helically arranged ridges 33 which are in turn provided with a plurality of suitably spaced longitudinally formed grooves 34, which results in the formation of the pick-up 75 teeth 30 for picking up the individual hairs as

described above. This results in the pick-up teeth 30 being progressively staggered around the circumference of the pick-up roller so that as the latter rotates each succeeding pick-up tooth or teeth will be somewhat spaced longitudinally 5 of the pick-up roller with relation to the next preceding tooth or teeth. This means that when the pick-up roller is rotated, as it will be by being driven through the gears 21, 26 and 23, from the power roller 19, the individual hairs of the head 10 being trimmed will be picked up and presented at approximately right angles to the plane of the cutting edge of the blade.

In the operation of my device it will from the foregoing be understood that when trimming the 15 hair on the head preferably of a human being, the power roller 19 will be pressed against the head and moved downwardly over the hair with sufficient pressure to cause positive rotation of the power roller in the direction of the arrow in Fig. 20 3, which through the medium of gear wheels 21, 26 and 23 will impart rotation to the pick-up roller 18 in the direction of the arrow in Fig. 3, and in turn cause the pick-up teeth 30 to pick up the individual hairs 35 and carry them individually, as shown in Fig. 3, toward the cutting edge of 25 the blade and present them thereto at substantially right angles which, as is obvious, is the most advantageous position of the hairs with relation to the cutting blade to facilitate ease of cutting. 30 This ease and efficient cutting will take place because of the forward movement of the cutting edge of the blade over the head, which forward movement, as explained above, results in the rotation of the power roller and the pick-up roller. 35 As shown in the drawing, the driving gears will be so proportioned and arranged as to drive the pick-up roller at a higher rate of speed of rotation than that of the power roller, this increase in speed being capable of any desired ratio with 40 respect to the rotation of the power roller as desired, depending upon the relative size of the gears.

While I have shown in the drawing for illustrative purposes a particular arrangement of the 45 pick-up teeth of the pick-up roller which I have found to be highly satisfactory, I wish it understood that my invention comprehends other possible arrangement or arrangements of such pick-up teeth capable of producing the effective picking up of the individual hairs and presenting them substantially at right angles to the cutting edge of the blade.

Other means for rotating the pick-up roller 18 may also be employed, such, for example, as 55 power means illustrated in the modification of Fig. 5. In this form I have shown for illustrative purposes a motor casing 36, which may house any desired form of motor, such as an electric motor, spring motor, or the like, mounted upon shaft 37 and driving gear 38, which meshes with gear 23 for directly or otherwise driving the pick-up roller 18. In this form the power roller 19 is omitted and in order to provide a suitable fulcrum in the advance portion of the device I have 60 provided spring fingers 39, suitably spaced in any desired number along and fastened to a bar 40 secured at its ends in side plates 6 and 7, which at their forward ends may be somewhat shorter in length because of the omission of the 65 power roller 19. It will be understood that when an electric motor is used in casing 36, suitable electrical connections will be provided thereto for connection with the ordinary electric socket in the home. With this arrangement last de- 75

scribed the pick-up roller 18 may be rotated at a greater or less speed as desired.

Having now described my invention,

I claim:

5. 1. In a hair trimmer, a cutting blade, holding means for said blade, and a pair of rollers in advance of the cutting edge of said blade, one of said rollers contacting the surface to be trimmed and driving the other roller.
10. 2. In a hair trimmer for trimming the hair on a human head, a cutting blade, a holder for said blade, a traction roller in advance of the cutting edge of said blade and adapted to be rotated by rolling contact with the head, and a pick-up roller between said traction roller and said cutting edge.
15. 3. In a hair trimmer for trimming the hair on a human head, a cutting blade, a holder for said blade, a traction roller in advance of the cutting edge of said blade and adapted to be rotated by rolling contact with the head, and a pick-up roller between said traction roller and said cutting edge, and means for rotating said pick-up roller from said traction roller but at a greater speed.
20. 4. In a hair trimmer for trimming the hair on a human head, a cutting blade, a holder for said blade, a traction roller in advance of the cutting edge of said blade and adapted to be rotated by rolling contact with the head, and a pick-up roller between said traction roller and said cutting edge, and means for rotating said pick-up roller from said traction roller but at a greater speed, the direction of rotation of said pick-up roller being such as to carry its upper portion toward said cutting edge.
25. 5. In a hair trimmer for trimming the hair on a human head, a blade, a holder for said blade, a pick-up roller adjacent the cutting edge of said blade and having progressively offset teeth around its circumference, and a power roller in advance of said pick-up roller, means for driving said pick-up roller from said power roller, said power roller acting as a fulcrum against the head for controlling the coarseness of cut.
30. 6. In a hair trimmer for trimming the hair on a human head, a cutting blade, a holder for said blade, a framework attached to said holder, a pair of rollers rotatably mounted in said framework in advance of the cutting edge of said blade, one of said rollers being mounted ahead of the other one and said other roller being mounted closely adjacent the cutting edge of said blade, the forward roller having traction means for causing its rotation as it is rolled over the head, and means for driving the other roller from said forward roller.
35. 7. In a hair trimmer for trimming the hair on a human head, a cutting blade, a holder for said blade, a framework attached to said holder, a pair of rollers rotatably mounted in said framework in advance of the cutting edge of said blade, one of said rollers being mounted ahead of the

other one and said other roller being mounted closely adjacent the cutting edge of said blade, the forward roller having traction means for causing its rotation as it is rolled over the head, and means for driving the other roller from said forward roller, said other roller being provided with means for picking up the hairs and presenting them to the cutting edge of the blade.

8. In a hair trimmer for trimming the hair on a human head, a cutting blade, a holder for said blade, a framework attached to said holder, a pair of rollers rotatably mounted in said framework in advance of the cutting edge of said blade, one of said rollers being mounted ahead of the other one and said other roller being mounted closely adjacent the cutting edge of said blade, the forward roller having traction means for causing its rotation as it is rolled over the head, and means for driving the other roller from said forward roller, said other roller being provided with means for picking up the hairs and presenting them to the cutting edge of the blade, the means on said other roller for picking up the hair comprising projections progressively offset circumferentially of the roller.

9. In a hair trimmer for trimming the hair on a human head, a cutting blade, a holder for said blade, a pair of depending plates on said holder, a pair of rollers rotatably mounted in said plates, one of said rollers forming a pick-up roller adjacent the cutting edge of the blade, and the other roller being in advance of said pick-up roller and being rotated by rolling contact with the head, means for driving the pick-up roller from the forward roller, the forward roller having circumferentially arranged projections to increase the rolling contact with the head, the pick-up roller having teeth progressively circumferentially offset from each other to pick up the hairs and present them to the cutting edge of said blade, the speed of rotation of the pick-up roller being greater than that of the forward roller.

10. In a hair trimmer for trimming the hair on a human head, a cutting blade, a holder for said blade, a pair of depending plates on said holder, a pair of rollers rotatably mounted in said plates, one of said rollers forming a pick-up roller adjacent the cutting edge of the blade, and the other roller being in advance of said pick-up roller and being rotated by rolling contact with the head, means for driving the pick-up roller from the forward roller, the forward roller having circumferentially arranged projections to increase the rolling contact with the head, the pick-up roller having teeth progressively circumferentially offset from each other to pick up the hairs and present them to the cutting edge of said blade, the speed of rotation of the pick-up roller being greater than that of the forward roller, the direction of movement of the upper portion of said pick-up roller being toward the cutting edge of the blade.

LEONARD A. GESLER.
